CHILD'S AUTOMOBILE SEAT

Benny A. Joines, 9385 Willow Grove, Santee, Calif.

Filed Mar. 7, 1960, Ser. No. 59,639

Term of patent 7 years

(Cl. D15—1)

Fig. 1

Fig. 2

Fig. 3

I claim:

The ornamental design for a child's automobile seat, as shown.
